UNITED STATES PATENT OFFICE.

GIUSEPPE CANNATA, OF CHICAGO, ILLINOIS.

DESIGN FOR A CLOCK-FRAME.

40,574.

Specification for Design.

Patented Mar. 15, 1910.

Application filed July 29, 1909. Serial No. 510,346. Term of patent 14 years.

To all whom it may concern:

Be it known that I, GIUSEPPE CANNATA, a subject of the King of Italy, residing at Chicago, in the county of Cook and State of Illinois, have invented a new, original, and ornamental Design for Clock-Frames, of which the following is a specification, reference being had to the accompanying drawing, forming a part thereof, and which represents in plan view my new design.

The design consists of the clock frame of the configuration shown in the drawing.

I claim:

The ornamental design for a clock frame, as shown and described.

GIUSEPPE CANNATA.
